UNITED STATES PATENT OFFICE.

ARTHUR LOPEZ JIMENEZ, OF NEW YORK, N. Y., ASSIGNOR OF FORTY-FIVE ONE-HUNDREDTHS TO WILLIAM FREEMAN AND FIVE ONE-HUNDREDTHS TO JOSEPH LOPEZ JIMENEZ, OF NEW YORK, N. Y.

WHEEL.

No. 888,504.

Specification of Letters Patent.

Patented May 28, 1908.

Application filed April 6, 1907. Serial No. 386,811.

To all whom it may concern:

Be it known that I, ARTHUR LOPEZ JIMENEZ, of New York, in the county of New York and State of New York, have invented 5 certain new and useful Improvements in Wheels; and I do hereby declare the following to be a full, clear, and exact description of the invention, such as will enable others skilled in the art to which it appertains to 10 make and use the same.

My invention relates to an improvement in wheels particularly adapted for use in motor vehicles of any description and it consists in the parts and combinations of parts 15 and in the details of construction as will be more fully explained and pointed out in the claims.

In the accompanying drawings, Figure 1 is a view in elevation of my improved wheel. 20 Fig. 2 is a view in transverse section of the same. Fig. 3 is a view in elevation of the spokes, rigid felly and hub-plates to which the inner ends of the spokes are secured. Fig. 4 is a view in section of the same. Fig. 25 5 is a view in elevation of the cushion tire casing detached. Fig. 6 is a view in section of the same, and Fig. 7 is a view of a section of this casing taken from its inner or concave side.

30 1 represents the spokes, preferably made of tubular steel and secured at their inner ends to the plates 2 by bolts 3 and nuts 3^a, the bolts passing through both plates and spokes and serving to clamp the parts firmly 35 together. I prefer to provide the inner end of the spokes which are slightly flattened at their sides, with a wood filling to prevent undue compression. The plates 2 may be integral with the hub or separate therefrom. 40 and secured thereto in any manner, but I prefer to have them independent of the hub so as to permit the spokes to be tightly clamped thereto before assembling on the hub.

45 Secured to outer ends of the spokes 1 is the tubular felly 4 which latter is preferably made of steel and is secured to curved plates 5 on the ends of the spokes, by rivets or screws. The spokes 1 are provided between 50 the felly and hub with the annular shoulders 6 and between the shoulders 6 and felly 4 are recesses 7 in which anti-friction balls 8 are located. Mounted on the felly and spokes thus assembled, is the cushion tire composed 55 of a casing or frame 9, embracing the felly

and outer ends of the spokes, a pneumatic cushion 10, and a tire 11 located on a rigid seat 12 outside, the cushion and clamped between the outer edges of the casing or frame, as clearly shown in Fig. 2. This casing or frame 9 is made up of two annular plates made of metal and secured together at their inner edges by screws or rivets, and provided between said screws or rivets with openings 13 which latter are of a width to 60 snugly seat the spokes but are considerably longer than the diameter of the spokes so as to permit a free cushioning movement of the cushion tire on the felly and spokes. 65

Each ring plate is bulged outwardly, as 70 shown at 14, to receive the felly 4 and pneumatic cushion 10 and permit of free and ample movement of the latter within said ring plates, and the outer free edges of said plates 75 9 are bent to form clamping flanges 15 which engage the side edges of the tire and lock the latter in place. This tire 11 may be made of wood, rubber, or any other material and may be in the form of a ring or made up of sections. Located within the space between the plates 80 9 and outside of, or encircling the cushion 10 is the steel band or tire seat 12 which latter operates to restrain outward movement of cushion 10 and forms a continuous seat for the tire 11. The ring plates 9 are secured 85 together, between the spokes, by the screw bolts 16 and are secured outside of the seat 12 inside the tire by the screw bolts 17, the anti-friction balls 8, previously referred to, bearing against the plate 9, as shown in Fig. 90 2, and operating to reduce to a large extent the friction between the plates and spokes. When the parts are thus assembled, and the pneumatic cushion 10, which may be of any approved form, is inflated, the felly 4 will 95 rest well within the enlargement or bulge 14, formed in the tire casing, and the inner periphery of the tire casing will be considerably removed from the shoulders 6. It will thus be seen that as the cushion gives under the weight 100 of the vehicle the vertical spokes or the spokes in the plane of the point of traction of the wheel, will move inwardly, the movement being always cushioned by the pneumatic cushion 10. This movement however is never sufficient to bring the shoulders 6, which are faced with leather or other suitable cushioning material, into contact with the inner periphery of the ring, unless the cushion 10 should lose its air, in which event the ring 110

will bear against the shoulders 6 and thus enable the vehicle to be run, if necessary, to a point where the machine could be repaired or the cushion 10 inflated. The spokes other than the ones immediately above the point of traction have more or less movement laterally within the openings 13 and this is provided for by making said openings greater in length than in width, as clearly shown in Fig. 7. With this construction the cushion which is the only part liable to injury, is completely housed and protected and consequently is not liable to be punctured. It operates however by its location between the felly and rim to permit of a free yielding movement of the rim and consequently possesses the same advantage as the ordinary pneumatic tire.

It is evident that many slight changes might be made in the relative arrangement of parts shown and described without departing from the spirit and scope of my invention hence I would have it understood that I do not wish to confine myself to the exact construction of parts shown and described, but,

Having fully described my invention what I claim as new and desire to secure by Letters-Patent, is:—

1. The combination with spokes each having an annular shoulder between its ends and a rigid felly secured to the outer ends of said spokes, of a casing embracing the felly and the outer ends of the spokes, a tire carried by said casing and a cushion within the casing between the felly and tire.

2. The combination with the shouldered

spokes and rigid felly secured thereto, of the two part casing embracing the felly and outer ends of the spokes the openings in the casing through which the spokes pass being longer than the diameter of the spokes, anti-friction balls interposed between the spokes and side walls of the casing within the spoke openings, a tire carried by said casing, and a cushion within the casing between the tire and felly.

3. The combination with spokes, each having shoulders between its ends, clamping plates engaging the inner ends of the spokes and a felly secured to the outer ends of the spokes, of a two-part casing shaped substantially as shown and embracing the felly and outer ends of the spokes and having openings for the free passage of the spokes, the said openings being of greater length than width, a tire secured to the periphery of the casing, and a cushion interposed between said tire and felly.

4. The combination with the shouldered spokes, clamping plates secured to the inner ends thereof and a felly secured to the outer ends, of the two-part casing embracing the felly and outer ends of the spokes, each member of said casing having a hook shaped outer edge, a tire clamped between said hook-shaped outer edges, and a cushion interposed between said felly and tire.

In testimony whereof, I have signed this specification in the presence of two subscribing witnesses.

ARTHUR LOPEZ JIMENEZ.
